F. D. BEARLY

DERRICK

Filed Feb. 9, 1924

UNITED STATES PATENT OFFICE.

FRED D. BEARLY, OF OKLAHOMA CITY, OKLAHOMA.

DERRICK.

Application filed February 9, 1924. Serial No. 691,587.

To all whom it may concern:

Be it known that I, FRED D. BEARLY, a citizen of the United States, residing at Oklahoma City, in the county of Oklahoma and

5 State of Oklahoma, have invented certain new and useful Improvements in Derricks; and I do hereby declare the following to be a full, clear, and exact description of the invention, such as will enable others skilled 10 in the art to which it appertains to make and use the same.

My invention relates to derricks for oil, gas or artesian wells, and is especially concerned with features of construction more 15 particularly designed to strengthen the derrick at the point where it is necessary to provide an opening or window in order to afford operating space for a walking beam or the like.

20 The principal object of the invention is to provide simple and efficient means for resisting buckling of the derrick legs toward the opening provided for the walking beam, although it is to be understood that the 25 means for strengthening the derrick hereinafter described and claimed are not limited in application to the particular relation illustrated in the single embodiment of the invention appearing in the drawings.

30 The principal feature of the invention, generally stated, consists in forming the derrick with a plurality of legs between adjacent ones of which a pair of transversely extending jack girds are arranged, the said 35 jack girds being spaced apart at their inner ends to permit a walking beam or the like to operate between them, and being respectively connected at their outer ends to the correspondingly adjacent legs of the derrick, tension members being combined with the jack girds and the adjacent derrick 40 legs to form truss structures.

A further feature of the invention consists in providing a derrick having a plurality 45 of legs with a pair of jack girds arranged on the same side of the derrick and connected at their outer ends to respectively adjacent derrick legs, the inner ends of the jack girds being spaced apart to enable a 50 walking beam to operate between them, tension members being provided for respectively cooperating with the jack girds and the adjacent derrick legs to form trusses, and a plurality of obliquely extending braces 55 being employed for connecting the legs with which the jack girds cooperate, said braces

forming tension members which are arranged in pairs, and the braces of each pair being divergent from the outer end of one of the jack girds toward the derrick leg 60 with which the opposite jack girth is associated.

A further feature of the invention consists in forming the derrick legs with a plurality of abutting sections arranged in alinement, and in providing bracing means for adjacent leg sections comprising a transversely extending jack girth supported at its outer end upon a leg of the derrick substantially at the abutting ends of said adjacent 65 leg sections, combined with obliquely extending tension members connecting the jack girth and the adjacent leg sections to form a truss, the inner end of the jack girth terminating in spaced relation to the opposite derrick leg.

A still further feature of the invention, particularly applicable to the type of derrick shown in the drawings, involves the use of a continuous lock wire which passes through 80 the openings of the turnbuckles of the oblique braces of the derrick to retain said turnbuckles in adjusted relation.

In the preferred embodiment of the invention illustrated in the drawings, —

85 Figure 1 is an elevational view of the front of a derrick constructed in accordance with the invention.

Figure 2 is a detail elevation of a portion of the construction shown in Fig. 1.

90 Figure 3 is a detail perspective view showing the relation of certain of the girds and braces to one of the derrick legs.

95 Figure 4 is a detail view, partly in elevation and partly in section, showing the inner end of one of the jack girds and the relation of certain braces thereto.

The type of derrick illustrated in the drawings for the purpose of explaining the invention, is commonly known as the standard drilling derrick. It is provided with a plurality of legs 1 arranged in the form of a pyramid having a square base. In order that it may be erected with a minimum amount of labor and be readily taken down 100 for removal to another place of use, each of the derrick legs is preferably formed of a series of abutting sections which are disposed in longitudinal alinement. The lowermost sections or starting legs 2 of the derrick legs 1 are somewhat longer than the 105 succeeding upper leg sections 3. The leg

sections are connected at their abutting ends, an advantageous means for effecting such connection being to employ angle shaped corner irons 4 and cooperating bolts 5 of the 5 character disclosed in the Slater Patent No. 1,099,771, dated June 9, 1914.

Transversely extending vertically spaced girders 6 are employed to connect the derrick legs at the joints between the abutting leg sections. These girders may be conveniently fashioned as tubular members having slotted flattened ends which interlock with each other and with the adjacent leg sections of the derrick in the manner set forth in the 15 Slater patent already mentioned. Tension members formed from sections of steel rods adjustably connected by turnbuckles 8 and having hooked ends enabling them to be detachably connected to the angle shaped corner braces 4, serve as oblique or diagonal braces for connecting the adjacent legs of the derrick.

The starting legs 2 at the front of the derrick are commonly connected by a set of transverse braces 9 and 10 termed respectively, first and second raised girders, while the derrick leg sections 3 immediately above the starting leg sections 2 are similarly transversely connected by braces 11 commonly called third raised girders. The walking beam (not shown) projects into the derrick in the interval between the second and third raised girders at a point opposite the upper ends of the starting legs 2.

35 In order to prevent the derrick legs from buckling in at the joints between the starting legs 2 and the leg sections 3 immediately above them, the derrick is provided with a pair of transversely extending jack girders 12 which have abutment reactions at their outer ends against the respective derrick legs 1 and whose inner ends are spaced apart a sufficient distance to afford clearance for the proper operation of the walking beam. The jack girders 12 may advantageously be formed as tubular members having flattened and slotted ends similar to those provided for the transversely extending tubular girders 6, the flattened outer ends 40 of said jack girders being adapted to interlock with the adjacent leg sections of the derrick and with the neighboring end of the adjacent girder 6 in the same manner as the girders 6 interlock with each other and with the leg sections of the derrick. Each jack girder 12 is connected to the adjacent leg sections 2 and 3 with which it is associated by obliquely extending means constituting the tension member element of a truss in 45 which the jack girder forms the strut and the adjacent leg sections form the compression member. The tension element of the truss is preferably constructed as a plurality of oblique tension members 13 formed of rod sections which are adjustably connected by

means of turnbuckles 14. The inner end of each of the oblique bracing members 13 preferably is detachably connected to the inner end of the adjacent jack girder 12, such connection being effected by providing the truss rods 13 with hooked ends 15 which enter the open inner end of the jack girder, as well shown in Fig. 4.

Connected to each derrick leg adjacent the point where the outer end of the corresponding jack girder 12 is connected thereto, is a pair of obliquely extending tension members 16 forming tension braces connecting the derrick legs 1 with which the jack girders cooperate. These braces 16 are disposed on opposite sides of the respective jack girders and diverge from the outer end of one jack girder 12 toward the derrick leg 1 with which the other jack girder is associated. The oblique tension member braces 16 are preferably formed as rods connected by adjusting turnbuckles 8, their free ends being formed with hooks which enter apertures in the neighboring angle plates or brackets 4 to provide connections with the derrick legs through said brackets.

As shown in the drawings, the turnbuckles of the oblique tension braces 7 and 16 are preferably disposed in substantially the same line so that after these turnbuckles 45 have been adjusted a continuous lock wire, such as 17, may be passed through the turnbuckle openings to maintain them in adjusted position. The turnbuckles 14 of the oblique tension members 13 cooperating with one of the jack girders 12 may also conveniently be positioned so that the lock wire 17 may likewise serve to retain them in adjusted position. This is a very simple construction for preventing loosening of the turnbuckles and is advantageous in that it affords a visible indication that the turnbuckles are in proper adjusted relation.

It will be perceived by those familiar with the construction of drilling derricks that my invention provides means for efficiently strengthening derrick construction at a point where failure is liable to occur, and eliminates any weakness which otherwise might be occasioned by the provision of the opening or window for the operation of the walking beam.

I claim:

1. A derrick involving a plurality of legs, a plurality of vertically spaced girders connecting said legs, a pair of jack-girders arranged between adjacent girders on the same side of the derrick, said jack-girders being spaced apart at their inner ends to permit a walking-beam or the like to operate between them and being respectively connected at their outer ends to the correspondingly adjacent legs, and tension members respectively cooperating with said jack-girders and the adjacent derrick legs to form trusses. 130

2. A derrick involving a plurality of legs, a plurality of vertically spaced girths connecting said legs, a pair of jack-girths arranged between adjacent girths on the same side of the derrick, said jack-girths being connected at their outer ends to respectively adjacent derrick legs and being spaced apart at their inner ends to permit a walking-beam or the like to operate between them, tension members respectively cooperating with said jack-girths and the adjacent derrick legs to form trusses, and a plurality of obliquely extending braces forming tension members connecting said legs with which said jack-girths cooperate, said braces being arranged in pairs and being disposed on opposite sides of said jack-girths, and the braces of each pair being divergent from the outer end of one of said jack-girths toward the derrick leg with which the other jack-girth is associated.
3. A derrick involving a plurality of legs, each of said legs including a plurality of abutting sections arranged in longitudinal alinement, and bracing means for connecting adjacent leg sections, said means comprising a transversely-extending jack-girth supported at its outer end upon a leg of the derrick substantially at the abutting ends of said adjacent leg sections and terminating at its inner end in spaced relation to the opposite derrick leg, and obliquely extending tension member means operatively connecting said jack-girth and said adjacent leg sections to form a truss therewith.
4. A derrick involving a plurality of legs including a sectional leg comprising a plurality of sections arranged in longitudinal alinement, and means for bracing adjacent sections of said sectional leg, said means including a girth member associated with said adjacent leg sections, and means cooperating with said girth member and with said leg sections to form a truss, the said girth member operating as a strut.
5. A derrick involving a plurality of legs, transversely extending girths connecting said legs, obliquely disposed braces connecting said legs, and a plurality of trusses spaced apart at their inner ends to provide an opening for the operation of a walking-beam or the like, portions of said derrick legs forming compression elements of the respective trusses, and said trusses each involving a strut and a tension element engaging said strut.
6. A derrick involving a plurality of sectional legs, a plurality of jack-girths spaced apart at their inner ends, and having their outer ends respectively connected to the correspondingly adjacent derrick legs, and a plurality of obliquely disposed tension members connecting each of said jack-girths with the adjacent derrick leg, the inner ends of the tension members associated with each jack-girth being connected to the latter, said tension members being connected at their outer ends to sections of the adjacent derrick leg on opposite sides of the jack-girth with which said tension members cooperate, and said tension members including means for adjusting the tension thereof.

In testimony whereof I affix my signature.

FRED D. BEARLY.
